UNITED STATES PATENT OFFICE

149,098

DESIGN FOR A ROCKING HORSE

Sylvia Stein, Chicago, Ill., assignor to Roxy Manufacturing Company, Chicago, Ill., a co-partnership comprised of Sylvia Stein, Emanuel T. Batko, and Al Stillman

Application April 24, 1946, Serial No. 128,921

Term of patent 3½ years

(Cl. D34—15)

To all whom it may concern:

Be it known that I, Sylvia Stein, a citizen of the United States and resident of Chicago, in the county of Cook and State of Illinois, have invented a new, original, and ornamental Design for a Rocking Horse, of which the following is a specification, reference being had to the accompanying drawing, forming a part thereof.

The figure is a perspective view of a rocking horse showing my new design, the opposite side being identical with that disclosed.

I claim:

The ornamental design for a rocking horse, substantially as shown and described.

SYLVIA STEIN.
